UNITED STATES PATENT OFFICE.

TOD J. MELL, OF AKRON, OHIO, ASSIGNOR TO THE B. F. GOODRICH COMPANY, OF NEW YORK, N. Y., A CORPORATION OF NEW YORK.

VARIEGATED ARTICLES OF RUBBER OR THE LIKE AND METHOD OF MAKING THE SAME.

Application filed July 9, 1925. Serial No. 42,451.

This invention relates to the art of producing variegated articles of plastic material having marbled, mottled or grained color effects, and is of especial value in the production of rubber sheeting having such color effects. The present invention is an improvement upon that of my United States Patent No. 1,588,797, granted June 15, 1926.

The chief object of my present invention is to provide a new and improved method of making articles such as rubber sheeting whereby novel and pleasing color effects may be obtained, and more particularly marbled, grained or mottled effects. Further objects 15 are economical production and an improved product.

I am aware that heretofore rubber sheeting of mottled or marbled appearance has been produced by mixing rubber particles of 20 different colors and sheeting the mixture between rolls to produce a single-thickness sheet, but this procedure is slow and expensive as compared with my method, does not readily afford so wide a range of color 25 effects, and does not provide so close an imitation of natural marble. I have found that by mixing differently colored masses of vulcanizable rubber compounds, sheeting the mixture, preferably between calender rolls, 30 and then splitting or slicing the sheet into thinner sheets, a very superior imitation of marble, as well as various other striking color 35 effects may be obtained, and with economy of production, the difference in surface design or appearance apparently being due to the fact that the action of the calender rolls produces a smearing and thinning out of the margins of the color zones at the surface of the sheet which does not occur in 40 the same form within the body of the sheet, wherefore the splitting of the latter exposes a more clear cut and pleasing surface design. Different bloom characteristics in the 45 rolled surface and in the cut surface of the rubber also may be of some effect in accounting for the different surface appearance obtained.

Of the accompanying drawings:

Fig. 1 is a perspective view of parts of a 50 calender and the work therein, showing a preferred form of procedure in accordance with my invention.

Fig. 2 is a perspective view of the work illustrating different color effects obtained

by slicing the relatively thick stock sheet 55 into thinner sheets.

Fig. 3 is a vertical section of preferred apparatus for slicing the stock sheet, and the work therein.

Different types of mixtures are of course 60 employed according to the color design desired. I find that one of the more common and popular marble effects may be obtained, for example, by loosely rolling or folding together a light colored sheet of compound 65 10 and a dark colored sheet 11 as shown in Fig. 1 of the accompanying drawings and feeding the rolled or folded sheets end first through the calender, the rolls of which are shown at 12, 13, 14. The usual liner is shown 70 at 15 for carrying the calendered sheet 16 from the calender.

The calender rolls are so set as to produce a sheet 16 sufficiently thick to be sliced into two or more thinner sheets, 17, 17, Fig. 2, 75 and the sheet 16 preferably is at least partially vulcanized before the slicing operation in order to set it and thus permit it to be cut without permanent distortion or disarrangement of the color elements therein. 80

The slicing operation is most satisfactorily performed by means of apparatus similar to a common type of leather splitting machine but preferably having integral presser rolls, adapted to confine the sheet and uniformly compress it flatwise at the line of cut and progressively release it for passage over the side faces of the knife as the line of cut advances, so as to avoid binding of the knife, as described in my above identified 85 copending applications, but I do not wholly limit my claims to the specific procedure or apparatus herein described for slicing the stock sheet.

The preferred apparatus for slicing the 95 stock sheet is shown in Fig. 3, wherein 18, 19 are a pair of knurled guiding and presser rolls, preferably driven at even speed, adapted to feed the stock sheet 16 against a band knife 20 mounted in a knife guide 21. 100 The usual guide plate 22 and means including feed screws such as the screw 23 are provided for slowly feeding the knife forward to keep the cutting edge of the knife at the proper position notwithstanding the 105 abrading away of the knife by the usual continuous-sharpening means.

The presser rolls 18, 19 are preferably set

- so close together with relation to the normal thickness of the stock sheet 16 as to reduce the thickness of the sheet at least three per cent as it passes between them, 5 the distance A, from roll to roll, being substantially less than the normal thickness of the sheet, which is indicated by the lines x, x , as I find that this facilitates the slicing action of the knife, apparently because 10 it provides in the nip of the rolls a zone of rubber which is virtually rigid with relation to the force of the knife in the plane of the cut, said zone acting somewhat in the manner of a backing plate for the action 15 of the knife, and because it apparently produces a tension in the rubber, in the direction of the thickness of the sheet at the line of cut, a normal cross-section of the sheet taking the position indicated by 20 the lines y, y , because of the volumetric incompressibility of the rubber, so that the cut surfaces do not bear strongly against the faces of the knife with the inward-rolling, friction-increasing effect which occurs 25 when a knife is simply forced against an unrestrained mass of rubber. After the slicing of the sheet the cut surfaces may be smoothed by abrasion or by further vulcanizing the sheet against a surfacing member.
- 30 Advantages of my present invention are that the differently colored compounds may be handled in mass, with resulting economy, as distinguished from the use of comminuted material; several sheets of the final product 35 may be obtained from a single calendered sheet; superior color effects may be obtained as compared with the effect obtained in a rolled surface; the different compounds are so arrayed or interspersed in the final product 40 as to provide a strongly laminated sheet; and a wide variation of detail in generally similar designs may be had in successive cuts from the same stock sheet.
- Modifications may be resorted to, both in 45 the manner of intermingling the compounds and in the slicing of the stock, without departing from the scope of my invention as claimed.
- I claim:
- 50 1. The method of making a variegated rubber article which comprises so mixing together a plurality of masses of rubber of different colors, at least one of the same being plastic, as to produce a mass of chance
- design in details of color arrangement, and 55 vulcanizing the mass, and thereafter removing material from the surface of the mass so produced to expose the internal structure thereof as a surface of the article.
2. The method of making a variegated 60 rubber article which comprises mixing together plastic rubber compounds of different colors, vulcanizing the mixture, and thereafter removing material from the surface of the resulting mass to expose the internal structure thereof as a surface of the article.
3. The method of making variegated rubber sheeting which comprises mixing together plastic rubber compounds of different colors, sheeting the resulting mass by 70 rolling pressure, vulcanizing the resulting sheet, and thereafter slicing the resulting sheet into a plurality of thinner sheets.
4. The method of making variegated rubber sheeting which comprises so mixing together a plurality of masses of rubber of different colors, at least one of the same being plastic, as to produce a mass of chance 75 design in details of color arrangement, sheeting the resulting mass by rolling pressure, subjecting the resulting sheet to vulcanization, and slicing the resulting sheet into a plurality of thinner sheets.
5. An article of manufacture comprising 80 a body of rubber produced by so mixing a plurality of masses of rubber, at least one of the same being in plastic form, as to produce a plastic mass of chance color design, vulcanizing said mass and removing 85 material from the surface thereof to expose its internal structure.
6. Rubber sheeting consisting of a slice 90 taken from a vulcanized mass of rubber comprising a plurality of rubber compounds of different colors so mixed while at least one of them is in plastic form as to provide a chance color design upon the cut surface of the slice.
7. Rubber sheeting consisting of a slice 100 taken from a vulcanized mass of rubber comprising a plurality of rubber compounds of different colors so mixed while in plastic form as to provide a chance color design 105 upon the cut surface of the slice.
- In witness whereof I have hereunto set my hand this 1st day of July, 1925.
- TOD J. MELL.
